UNITED STATES PATENT OFFICE

ISAAC HARRIS, OF BUFFALO, NEW YORK, ASSIGNOR, BY MESNE ASSIGNMENTS, TO UNITED REPRODUCERS CORPORATION, OF ROCHESTER, NEW YORK, A CORPORATION
OF NEW JERSEY

DESIGN FOR A GRILLE FOR SOUND REPRODUCER

Application filed April 17, 1928. Serial No. 26,360. Term of patent 3½ years.

To all whom it may concern:

Be it known that I, ISAAC HARRIS, a citizen of the United States, residing at Buffalo, in the county of Erie and State of New York, have invented a new, original, and ornamental Design for Grille for Sound Reproducer (Case A), of which the following is a specification, reference being had to the accompanying drawing, forming part thereof, in which the figure is a perspective view of a grille for sound reproducer showing my new design.

I claim:—

The ornamental design for a grille for sound reproducer, substantially as shown.

ISAAC HARRIS.
